ERNEST A. LLEWELLYN, OF WILTON, MAINE.

MOCCASIN.

1,195,825.

Specification of Letters Patent. Patented Aug. 22, 1916.

Application filed March 24, 1915. Serial No. 16,627.

To all whom it may concern:

Be it known that I, ERNEST A. LLEWELLYN, a citizen of the Dominion of Canada, and a subject of the King of Great Britain, residing at Wilton, in the county of Franklin and State of Maine, United States of America, have invented certain new and useful Improvements in Moccasins; and I hereby declare that the following is a full, clear, and exact description thereof, reference being had to the accompanying drawings, which form part of this specification.

This invention relates to shoes or the like, and more particularly to moccasins; and the objects are to provide a moccasin or shoe of superior quality having a neat and attractive appearance and embodying in its construction a vamp including the quarters composed of a single piece of leather or other suitable material secured to the sole of the shoe with its upper edge free and continuous from heel to toe, and having an upper and toe-piece secured thereto by a seam, preferably a raised seam, extending around the shoe in such manner as to produce in the finished article a pliable shoe or moccasin that will be easy on the foot and comfortable to wear and will have an attractive and finished appearance, without the objectionable features which are incident to the gathering of the leather according to present methods of construction, which tend to make the shoe stiff and cause the raised seam around the toe to rip; these objectionable features being eliminated by my improved method of forming and sewing the vamp and other parts of the shoe or moccasin together.

The invention will first be hereinafter more particularly described, with reference to the accompanying drawings, which are to be taken as a part of this specification, and then pointed out in the claims at the end of the description.

In said drawings, Figure 1 is a perspective view of a moccasin embodying my invention; Fig. 2 is a longitudinal sectional plan view of the same; the section being taken on a line below the seam which connects the vamp with the upper and toe-piece shown in Fig. 2; Fig. 3 represents a plan view of a blank for a shoe or moccasin vamp and lower portion of the quarters of a shoe embodying my invention.

Referring to said drawings, in which the

same reference letters are used to denote corresponding parts in different views, the letter A may denote the vamp of a shoe or moccasin formed in one piece with the lower portion of the quarters, and B the upper in one or more sections extending around the shoe from the heel to a point in front of the usual ankle seam, where it is joined to a toe-piece C having a tongue D secured thereto. Said parts B, C and D may be of the form shown, or of any suitable form and are secured to the upper free edge of the vamp and lower portion of the quarters preferably by a raised seam *a* extending entirely around the shoe, as shown. The vamp A consists of a single piece of leather or other suitable material extending completely around the shoe; the ends of said piece meeting at the rear of the heel where they may be sewed or otherwise secured together, and the joint or heel seam may be covered by a back strap E, suitably stitched to give a neat and finished appearance.

A blank for the single-piece vamp is shown in Fig. 3 of the drawings, being cut from a piece of leather in approximately U-shaped form and having the outer edge thereof cut away at several points, as shown to adapt the cut away portions to be sewed together and the blank to be bent upon itself and its outer edge turned in or under the foot and secured to the sole of the shoe in the manner illustrated in Fig. 2 of the drawings, and to this end said outer edge has a V-cut *f* in each wing, the edges of which cut are to be sewed together and from this point said edge of one wing preferably extends in a straight line, as at *f*¹, to near the free end of the wing while the corresponding part *f*² of the other wing is preferably concave, and at the other termini of these straight and concave edges a portion of the blank is cut away, as at *f*³, in both wings, so as to leave a flap *f*⁴, and a free end of reduced width.

The outer edge of the blank at the junction of the two wings is cut away so as to leave a preferably rounded portion or tip *f*⁵ to which, when the blank is bent upon itself, the adjacent edges of the cut-away portions *f*⁶ are sewed, while the edges of the two wings are brought together and secured by a seam or stitches along a line extending lengthwise of the shoe, as shown in Fig. 2, while the inner edge of the blank is left free for the attachment thereto of an upper

section or sections B and toe-piece C, which may be united by a raised seam *a*, said seam extending entirely around the shoe as shown. As will be seen, the in-turned edge of the blank is so formed that there is no gathering of the leather, or no leather to take in, as in the usual method of construction, in which there is usually a lot of leather to be gathered in, which makes the shoe stiff and causes the raised seam around the toe to rip, whereas my improvement obviates the necessity for gathering the leather around the upper edge of the vamp as is usually necessary in the manufacture of shoes or moccasins according to methods in common use. The V-cut in each wing of the blank and the cut-away portions at each side of the tip *f*⁵ adapt the leather to be gathered so as to fit over the sole and to lie smoothly under the foot. As will be seen, the wing F¹ of the blank, which forms the outside of the vamp of the shoe and comes on the outside of the last is a little wider than the wing F² and has a straight edge *f*¹ where there is no leather to be taken in on the outside, except such as is taken in by the V-cut *f* at that side from which point said straight edge slants toward the heel, while the confronting concave edge *f*² of the other wing F² permits a gathering or taking in of the leather at that side so as to form an approximately straight seam from a point about midway of the shoe to the tip *f*⁵, and makes the blank fit snug to the last. The outer edge of the blank is cut away at *f*³ to allow the heel to be lasted in without the gathering of too much leather in or around the heel, and is cut away at *f*⁶ on both sides of the tip *f*⁵ to adapt said edge to come in on the bottom of the last, so that when the sole is sewed on the vamp the meeting line of these edges will come inside of the line of fastening that holds the sole on the vamp. In making the shoe, the edges of the V-cuts are first stitched together, then the heel seam is stitched, then the back strap E is stitched on, and then a suitable counter G is stitched in. The shoe is then stitched up the bottom to the cut-away portions on opposite sides of the tip *f*⁵ and then put on the last, and then the edges of the blank on opposite sides of the tip *f*⁵ are drawn down and stitched to the tip, thus adapting that portion of the lower edge of the vamp to fit snugly and dispense with a seam and strap down the toe as heretofore employed. The toe-piece C is then stitched to the tongue D, preferably by placing the lower edge of the tongue on top of the toe-piece so that the tongue will overlap the toe-piece, and the two parts may then be sewed together with lines of stitching, as shown; the toe-piece being laid on the last after the vamp is on, and then the upper B is laid on and these parts are sewed to the vamp, preferably by

a raised seam extending completely around the shoe. If desired, a sole of the Goodyear type may be sewed on by sewing through the single sole piece close to the vamp, and a heel of about two lifts, thus making a low heel which will afford comfort to the wearer and lessen the danger of slipping.

In a moccasin thus formed the leather along the upper edge of the vamp simply lays in the right place without the necessity of forcing or gathering the same, and it has a tendency to keep its shape more correctly and uniformly and to better advantage than in the case of vamps as heretofore constructed, and at the same time is more pliable than a moccasin as ordinarily constructed, and also presents a more neat and finished appearance.

It will also be understood that in the manufacture of shoes or moccasins embodying my invention leather or any other suitable material may be employed, and in the appended claims the word leather is intended to include any suitable material.

Having thus described my invention, what I claim as new and desire to secure by Letters Patent is:

1. A moccasin or shoe comprising a sole, a vamp including the lower part of the quarters composed of a single piece of leather, said vamp having a tip with cut away portions at each side thereof and a V-shaped cut at each side of said cut away portions drawn and sewed together, said vamp extending completely around the shoe and having the lower edges thereof drawn and secured together along a line extending from heel to toe lengthwise of the sole, and an upper together with a toe piece secured to the top edge of said vamp.

2. A moccasin or shoe comprising a sole, and a vamp including the lower part of the quarters composed of a single piece of leather cut out in U-shaped form, a portion of the outer edge of one wing thereof being straight and the corresponding portion of the outer edge of the other wing being concave, each wing having a V-cut therein at the terminal of the straight or concave edge farthest away from the free end of the wing.

3. A blank for a moccasin or shoe vamp consisting of a single piece of leather cut out in approximately U-shaped form, one wing being substantially a counter-part of the other and each having a V-cut in the outer edge thereof, said edge being also slightly cut away at some distance from and between said V-cuts to a point about midway of the blank so as to leave at said point a rounded portion or tip, whereby said outer edge of the blank is adapted to be turned under and sewed to the sole of the shoe in such manner as to secure the edges of said wings together on a line extending lengthwise of the shoe with said tip turned

under at the toe and secured to the adjacent cut-away portions or edges of said wings surrounding said tip.

4. A blank for a moccasin or shoe vamp 5 consisting of a single piece of leather cut out in approximately U-shaped form, a portion of the outer edge of one wing being straight and the corresponding portion of the other wing being concave, each wing 10 having a V-cut therein at the terminal of the straight or concave edge farthest away from the free end of the wing, said straight edge slanting from said V-cut toward the inner edge of the wing, each wing having the 15 edge portion thereof at the other terminal of the straight or concave edge cut away so as to leave the wing with a heel portion of reduced width; that portion of the blank between said V-cuts having its outer edge 20 cut away so as to leave about midway thereof a rounded part or tip, adapting the edges of said cut-away portions to be gathered around said tip and sewed thereto by bending the blank upon itself, said tip being 25 adapted to be turned under and secured to the sole at the toe of the shoe; the edges of the V-cuts being adapted to be sewed together and the outer edges of the two wings turned under and sewed together along a 30 line extending lengthwise of the shoe.
5. A blank for a shoe or moccasin consisting of a single piece of material of approximately U-shaped form, each wing having a V-shaped cut in its outer margin and its outer terminal cut away so as to leave a heel portion of reduced width. 35
6. A blank for a moccasin or shoe vamp
- consisting of a single piece of material cut out in approximately U-shaped form, a portion of the outer edge of one wing being straight and slanting toward the inner edge of the wing in the direction of the free end of the wing and the corresponding portion of the other wing being concave. 40
7. A blank for a moccasin or shoe vamp 45 consisting of a single piece of material cut in approximately U-shaped form, a portion of the outer edge of one wing being straight and slanting toward the inner edge of the wing in the direction of the free end of the wing and the corresponding portion of the other wing being concave, each wing having the edge portion cut away and slitted at its free end so as to leave a short flap and a heel portion of reduced width. 50
8. A blank for a moccasin or shoe vamp 55 consisting of a single piece of material cut out in approximately U-shaped form, the outer edge of one wing being straight for a portion thereof, and the outer edge of the other wing being concave for a portion thereof, each wing having a V-shaped cut therein at one terminal of said straight and concave portions, and having the edge portion cut away and slitted at the other terminal so as to leave a short flap and a heel portion of reduced width. 60

In testimony that I claim the foregoing as my own, I affix my signature in presence of two witnesses.
